FRACTIONAL CRYSTALLIZATION OF
WAXESEarl Petty, New York, N. Y., assignor to Alco
Products, Incorporated, New York, N. Y., a cor-
poration of Delaware

Application July 27, 1933, Serial No. 682,446

6 Claims. (Cl. 196—18)

My invention relates to a method of fractional crystallization of waxes and more particularly to a method of removing wax from hydrocarbon oils in stages in order to obtain segregated wax fractions.

Currently lubricating oils are made preponderantly from distillates procured by vacuum distillation. The lubricating oils are obtained by dewaxing two or more segregated fractions of lubricating oil-bearing distillates, namely, pressable wax distillate, slop wax, and vacuum steam refined stock. The pressable wax distillate is cold pressed to remove the wax and segregate the lubricating oil. The slop wax distillate is processed by a centrifugal operation in which residuum stock or vacuum steam refined stock and retarders such as "Paraflow" or filter aid systems are used. The vacuum steam refined stock is processed by centrifuging or by the use of a filter aid process employing wax precipitating retarders such as "Paraflow" or residuum retarder stock. "Paraflow" is the trade name for a wax-aromatic hydrocarbon condensation product which has the property of lowering the cold test by retarding the crystallization of waxes which may be present in the oil.

These conventional methods of processing distillates to produce lubricating oils have as their byproducts the regular market grades of waxes, namely crude scale wax, refined paraffin wax, and petrolatum.

In my co-pending applications, Serial No. 632-278, filed September 9, 1932, now Patent 1,940,015, issued December 15, 1933, and Serial No. 651-497, filed January 13, 1933; I have disclosed a process of dewaxing in which a normally gaseous diluent such as propane, is liquefied and a solution made therewith with a wax-bearing hydrocarbon oil. Upon chilling this solution, wax is precipitated, due to the fact that the diluent at low temperatures acts as an oil solvent and a wax anti-solvent. By means of my dewaxing process, I have been enabled to dewax the entire lubricating oil-bearing distillates in one fraction. This fraction includes all the wax distillate, the slop fraction, and the vacuum steam refined stock. The resulting characteristics as to viscosity, falls in the approximate range of 65 to 85 seconds, (Saybolt universal) at 210° F.

It will be obvious that the operation by which the entire lubricating oil-bearing distillates are dewaxed in a single operation has numerous advantages in so far as the lubricating oil component is concerned. The wax which results from these processes, however, is a mixture of

commercial paraffin wax and petrolatum, and the wax requires further special processing to isolate the different types of waxes. This has been a disadvantage. It may be desirable to dewax an entire wax-bearing lubricating oil fraction and then practice fractional crystallization on the wax only by diluting with a non-viscous oil such as gas oil or naphtha in the first stage of dilution and then dilute with propane thereafter in the subsequent stages.

One object of my invention is to provide a process for dewaxing hydrocarbon oils while crystallizing the wax fractionally in order to obtain grades of wax which will meet the standard specifications and quality with respect to paraffin.

Another object of my invention is to provide a method of precipitating waxes from hydrocarbon oils in a series of stages in order to obtain different grades of wax.

Another object of my invention is to provide a method of fractional crystallization of waxes in a lubricating oil dewaxing process which will produce an improved quality of petrolatum.

In general, my invention contemplates a dewaxing process in which a normally gaseous liquefied diluent is employed to make a solution of a wax-bearing oil and the diluent. The concentration of the solution is carefully controlled. The solution is chilled to predetermined temperatures at which I have found various types of waxes precipitate. It will be seen that the type of wax which will be obtained will be a function of the type of wax-bearing oil used, the concentration of the solution and the temperature to which the solution is chilled. The concentration of the solution and the temperature to which the solution is chilled can be controlled. The solution is chilled to a predetermined temperature to precipitate a desired type of wax which is then filtered from the solution and the remaining solution further chilled to further precipitate the wax in a stepwise manner.

The accompanying drawing represents a schematic view of one form of apparatus capable of carrying out my invention. More particularly, I use as a solvent a normally gaseous liquefied diluent. I prefer to use propane, though it is to be understood that any equivalent solvent having a boiling range falling between -65° F. and 32° F. may be used. Such hydrocarbon gases as butane, iso-butane, or mixtures thereof, either alone or with propane, would be effective in my process. It is possible to use ethane, though this has a lower boiling point than necessary, or mixtures of such compounds of acetone or other

chemical compounds which would serve as crystal accelerators, with desired portions of propane. The charge may be the wax solution obtained by dewaxing the entire lubricating oil bearing 5 fraction or cut in one operation taking the wax solution as a charging stock.

The normally gaseous liquefied diluent is stored in a tank 1. The stock to be dewaxed is stored in tank 2. Pump 3 pumps the oil to be dewaxed 10 from the tank 2 through line 4 to a mixing tank 5 where the propane from tank 1 is pumped by pump 6 through line 7 to a mixing tank 5. The ordinary blend comprises about 50% lubricating oil stock and 50% diluent by weight. The mixture 15 under pressure is passed through heating and blending equipment 8 to form a solution. The temperature is raised to a point well above the melting point of the wax, while sufficient pressure is maintained to keep the diluent in a 20 liquid state. I have found that a temperature range from 125° to 150° F. and a pressure range from 180 pounds to 250 pounds per square inch gauge will be involved. The solution is then 25 passed through a cooler 9 of any suitable type, and through line 10 into crystallizer evaporator 11. In the crystallizer evaporator, a portion of the propane is evaporated through line 12 which 30 communicates with separator 14 which is in communication with low pressure propane main 15. Any liquefied propane or oil carried overhead 35 through line 12 will be separated in separator 14 and be returned to evaporator crystallizer through line 16. The amount of chilling in evaporator crystallizer 11 is such that the solution will be chilled to a temperature range varying from 30° to 50° F. depending upon the type of oil being dewaxed. At this point, the solution is still 40 under pressure and a crystal type of wax will largely be precipitated.

40 The chilled oil-diluent solution containing precipitated crystalline wax is withdrawn from the evaporator crystallizer 11 through line 17 and is pumped by pump 18 through line 19 into filter 20. The wax-oil-diluent slurry from filter 20 is pumped 45 by pump 21 through line 22 into filter 23. The wax-oil-diluent slurry is pumped from filter 23 through line 24 by pump 25 through line 26 to filter 27. The filter structure involved in filters 20, 23, and 27 is that shown in my co-pending 50 application Serial No. 679,358, filed July 7, 1933. The filter arrangement comprises filter tanks in which edge filtration apparatus is installed. The filters are provided with means for keeping the wax in a slurry form by the addition of added 55 amounts of diluent. The filters are also provided with a "kick-back" arrangement or a method of introducing fluid in the reverse direction through the filter in order to clear the same. These details are disclosed in my last mentioned co-pending application. In this connection, however, it might 60 be well to point out that any diluent which is added to maintain the wax in the form of a slurry is added at a temperature from 10° to 20° F. or, if desired, at a lower temperature in order to prevent re-dissolving of the wax. The filters, of 65 course, will operate at pressures at or above the pressure of equilibrium for the temperature at which the separation is being made. The oil-diluent solution containing unprecipitated waxes 70 passes from filters 20, 23, and 27 into manifold 28 which enters crystallizer evaporator 29. The wax solution slurry is withdrawn from filter 27 through line 30 and pumped by pump 31 through line 32, through heat exchanger 33 in which the temperature 75 of the slurry is raised sufficiently to melt the

wax. The slurry is then passed through contactor 34 in which it is treated for color and then passed into steam still stabilizer 35 in which the propane is distilled off overhead through line 36, condensed in condenser 37 and accumulated in tank 38 from which it may be pumped by pump 39 to the propane working tank 1. The first wax fraction, preponderantly of the crystalline type and oil free, will be withdrawn from the bottom of stabilizer 35 through line 40. This wax will have a melting point falling within the range of 120 to 130° F.

The oil-propane solution is then chilled by evaporating a portion of the normally gaseous liquefied diluent in crystallizer evaporator 29. The propane being evaporated passes from the evaporator crystallizer through line 41 into separator 42 which communicates through line 43 to the low pressure propane main 15. Any liquid propane or oil carried overhead is separated in 20 separator 42 and is returned to the evaporator crystallizer through line 44. It will be observed that I have pointed out, in order to maintain the wax in the form of a slurry, I propose to add as needed, additional amounts of liquefied diluent. 25 The oil-diluent solution, therefore, entering evaporator crystallizer 29 may have a dilution which is too high. I propose, in evaporator crystallizer 29, to evaporate a sufficient amount of propane to adjust the concentration to the desired point, 30 which will depend, of course, on the type of charging stock. Obviously, evaporation of a large amount of propane will result in a temperature which will be too low for the desired fractional crystallization of the wax. I overcome this disadvantage by installing a heat exchanger 45 in evaporator crystallizer 29. Any suitable material to be cooled may be passed through pipe 46, through heat exchanger 45, in order to permit the desired concentration to be reached, while 40 allowing the temperature to fall within the range of 20° to 0° F. The concentration of the diluent which is desirable is again approximately 50% by weight to 50% by weight of the oil being dewaxed. The oil-diluent solution at proper temperature and proper concentration, is withdrawn from evaporator crystallizer 29, through line 47 and is pumped by pump 48 through line 49 to filters 50, 51 and 52. The diluent-wax-oil slurry passes between filters through lines 53 and 54. 50 The oil-diluent solution is withdrawn from filters 50, 51, and 52 into manifold 55 from which it passes to evaporator crystallizer 56. The wax solution slurry is withdrawn from filter 52 through line 57 and is pumped by pump 58 through heat exchanger 59 in which the temperature of the solution is raised in order to melt the wax, and the entire solution is contacted for color in contactor 60 and passed to steam still stabilizer 61, from which the propane is withdrawn overhead through line 62, condensed in condenser 63 and accumulated in tank 64 from which it may pass through line 65 to line 66 and will be pumped by pump 39 to propane tank 1. The second wax will be a paraffin wax of a lower melting point and is withdrawn from the stabilizer 61 through line 67 and will be passed to storage.

The filtration in filters 50, 51, and 52 is again conducted in such a manner as to permit the wax to remain in the form of a slurry. Due to the fact, however, that a lower temperature is now needed, I have found that it usually is not necessary to employ a heat exchanger in evaporator crystallizer 56. A portion of the propane is 75

- again evaporated from the oil-diluent solution until a temperature of from -20° F. to -40° F. is obtained. The chilled oil solution containing wax precipitated by the low temperature and by the oil solvent and wax anti-solvent qualities of the diluent at the low temperature, is withdrawn from evaporator crystallizer 56 through line 69 and pumped by pump 69 into filters 70, 71, and 72, passing between filters through lines 73 and 74. The dewaxed oil solution is withdrawn from filters 70, 71, and 72, and passed into manifold 75 which discharges to steam still stabilizer 76 in which the propane is distilled and passed overhead through line 77, through condenser 78, and accumulated in tank 79, from which it passes through line 80 into line 66 from which it is pumped by pump 39 to propane tank 1. The fully dewaxed oil is withdrawn from the bottom of the stabilizer 76 through line 81 and passed to storage. The wax slurry is withdrawn from filter 72 through line 82 and is pumped by pump 83 through heat exchanger 84 in which the temperature is raised in order to insure that the wax is melted. The wax is then contacted for color in contactor 85 and the slurry or solution is passed into steam still stabilizer 86 in which the propane is evaporated from the wax. The propane passes overhead through line 87 and is condensed in condenser 88 and accumulated in tank 89 from which it is withdrawn through line 90 to line 66 and pumped by pump 39 to propane tank 1. The wax which is withdrawn from the bottom of stabilizer 86 through line 91 is a highly refined petrolatum of an unusually low oil content and resembles beeswax in physical characteristics.

It is to be understood, of course, that any number of suitable stages of wax crystallization may be employed in order to obtain different types of waxes which may be useful in the different arts. The resulting oil is fully dewaxed.

It will be understood that certain features and sub-combinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

- 55 1. The method of dewaxing a hydrocarbon oil including the steps of chilling a solution of wax bearing oil in a liquefied normally gaseous diluent

by evaporating a portion of the liquefied normally gaseous diluent sufficient to produce a solution of predetermined concentration, adding heat to the solution during chilling in sufficient quantity to prevent the temperature of the solution from dropping below a predetermined low temperature and separating precipitated wax from the chilled solution. 5

2. The method of dewaxing a hydrocarbon oil including the steps of chilling a solution of wax bearing oil in a liquefied normally gaseous diluent to a predetermined low temperature, separating from the chilled solution wax precipitated by the chilling, further chilling the partially dewaxed solution by evaporating a portion of the liquefied normally gaseous diluent sufficient to produce a solution of predetermined concentration while adding heat to the solution during chilling sufficient to prevent the temperature of the solution from dropping below a predetermined temperature lower than the first mentioned temperature and separating from the chilled solution wax precipitated during the last mentioned chilling operation. 10 15 20 25

3. A method as defined by claim 1 in which the normally gaseous liquefied diluent is a hydrocarbon which at wax precipitating temperatures exhibits wax anti-solvent, oil solvent properties. 25

4. A method as defined by claim 2 in which the normally gaseous liquefied diluent is a hydrocarbon which at wax precipitating temperatures exhibits wax anti-solvent, oil solvent properties. 30

5. The method of fractionally separating waxes from wax bearing hydrocarbon oils including the steps of dissolving a wax bearing oil in a liquefied normally gaseous diluent, chilling the solution to a predetermined wax-precipitating temperature, filtering the precipitated wax from the solution, recovering a first wax, chilling the partially dewaxed solution to a lower wax precipitating temperature at which a second type of wax precipitates by evaporating a portion of the normally gaseous liquefied diluent to an extent necessary to produce a solution of predetermined concentration while adding heat to the solution being chilled in sufficient quantity to prevent the temperature of the solution from dropping below the predetermined lower wax precipitating temperature, filtering the precipitated wax from the solution and recovering a second wax. 35 40 45 50

6. A method as in claim 5 in which the normally gaseous liquefied diluent is a hydrocarbon which at wax-precipitating temperatures exhibits wax anti-solvent, oil solvent properties. 55
